TUBE EXPANDER WITH HAMMER ACTION

Stanley J. Kay, Dearborn, Mich., assignor, by mesne assignments, to American Radiator & Standard Sanitary Corporation, New York, N. Y., a corporation of Delaware

Application September 7, 1954, Serial No. 454,483

1 Claim. (Cl. 153—30.5)

The present invention relates to a tube expander which is particularly but not exclusively adapted to be used with heat exchange tubes of the type that are normally encased in fins or baffles.

A problem exists in efficiently affixing fins to heat exchange tubes for items such as heaters or air conditioning units. Such fins are provided to obtain the maximum benefit from the heat exchange tubes, particularly in the situation where a fan or blower moves air over such tubes.

It is preferable to provide a heat exchange member from as few separate lengths of tube as possible in order to reduce the number of couplings required and the overall cost. The tool of the present invention permits the use of curved lengths of tube so that the number of separate tube sections required is minimized.

It is a principal object of the present invention to provide a tube expanding tool which is simple and economical to make and easy to maintain.

It is another object of the present invention to provide a tube expanding tool which may be efficiently used with a curved length of tube.

It is a further object of the present invention to provide a tube expanding tool which is rapid and easy to use.

Other objects of this invention will appear in the following description and appended claim, reference being had to the accompanying drawings forming a part of this specification wherein like reference characters designate corresponding parts in the several views.

In the drawings:

Fig. 1 is a front elevation of a heat exchange unit of the type with which the tube expanding tool of the present invention is used.

Fig. 2 is a fragmentary section of a tube and fin showing the tube expanding tool of the present invention in use.

Fig. 3 is a sectional view of the operating head of the tube expanding tool of the present invention.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring to the drawings, a heat exchange unit of the general type used with air conditioners is indicated at 10. The unit comprises a sinuous tubular heat exchange member composed of a series of hairpin tubes 12 coupled together with U-shaped couplings 14. A heating or cooling medium is passed through this tubular heat exchange member. A plurality of fins 16 are disposed over the tubes 12 and have suitable openings therein to accommodate said tubes.

2

The fins must be in tight engagement with the tubes, especially when air is moved over the tubes since such moving air will set up vibration in the fins if they are loose with resulting undesirable noise.

5 The tube expanding tool of the present invention is used to securely fasten the fins to the tubes. The tool is shown in detail in Fig. 3. It comprises a head 18 having a bullet-shaped nose 20 and a hammering collar 22. In a suitable tool now in use the diameter of the head is .010 inch smaller than the inside diameter of 10 the tube to be expanded, and the diameter of the hammering collar is such as to provide the desired diameter in the expanded tube.

The head 18 is provided with a chamber 24 having a 15 tapered end portion 26. A spindle 28 extends into the chamber 24 and is sufficiently smaller in diameter than the chamber to provide substantial clearance. The spindle 28 has a tapered end portion 30. In use, a 58 degree taper at 26 and a 60 degree taper at 30 have proven 20 satisfactory. This difference in angle and the clearance between the spindle 28 and the wall of chamber 24 cause the head 18 to produce a hammer effect which will be explained at a later point.

A pair of keys or keepers 32 and 34 extend from the 25 head 18 into slots 36 and 38 in the spindle 28 to prevent accidental removal of the spindle from the head. A flexible shaft 40 is affixed to the spindle 28. The shaft 40 can be of any desired length and is provided with suitable means for affixing it to a device such as an air-operated riveting hammer.

The tool is shown in operation in Fig. 2. As the air-operated riveting hammer is actuated, the head 18 is moved on the spindle due to the different tapers 26 and 35 30 (Fig. 3) and the clearance between the spindle 28 and the wall of chamber 24. This motion of the head pounds the hammering collar 22 against the sidewall of the tube and expands the tube to the desired diameter. This expansion moves the tube 12 into tight engagement with the fin 16.

40 The collar 22 on head 18 actually produces a hammering effect which permanently expands the tube material. This permits easy operation and withdrawal of the hammer since there is no spring-back of the tube. This feature also permits the tool to be used with a hairpin-shaped tube. In this manner, couplings 14 (Fig. 1) need be supplied at only one end of adjacent tubes. It is not necessary to use straight tubes with couplings at both ends.

45 The tube expanding tool of the present invention has proven that it will hammer tubes to fins securely and evenly to provide optimum efficiency and strength.

Having thus described my invention, I claim:

A tube-expanding tool for use in expanding the diameter of a tube along its entire length or any portion 50 thereof comprising a head having a blind chamber therein, a conical surface forming the blind end of said chamber, a spindle having one end extending into said chamber, said spindle being substantially smaller in diameter than said chamber to provide a substantial clearance between 55 said head and said spindle, a conically tapered surface formed on the end of said spindle which has an included angle greater than the included angle of the aforementioned conical surface and which lies adjacent thereto, and a hammering collar on said head near the front 60 thereof, movement of said spindle causing said head to actuate said hammering collar in a hammering action due to the clearance between said spindle and head and the difference in taper between said spindle end surface and chamber end surface.
